[57] CLAIM

The ornamental design for a flexible ski-carrier, as shown and described.

DESCRIPTION

FIG. 1 is a plan view of the inner face of a flexible ski carrier showing my new design in the open extended condition, the surface shading indicating a smooth shiny material;

FIG. 2 is a similar plan view of the reverse, outside face thereof, the surface shading indicating a woven fabric material;

FIG. 3 is a perspective view thereof in working condition wrapped about a pair of skis which form no part of my design and is indicated by broken lines; and
FIG. 4 is a perspective view thereof in rolled compact condition when not in use.

FIG. 1.

FIG. 2.

FIG. 4.

FIG. 3.
